UNITED STATES PATENT OFFICE.

JOHN PARK, OF NEW YORK, N. Y.

PORTRABLE JOINT FOR ROPES, WIRE, AND THE LIKE.

1,159,863.

Specification of Letters Patent.

Patented Nov. 9, 1915.

Application filed April 25, 1913. Serial No. 763,556.

To all whom it may concern:

Be it known that I, JOHN PARK, a resident of the city of New York, in the State of New York, United States of America, have invented certain new and useful Improvements in Portable Joints for Ropes, Wire, and the like; and I do hereby declare that the following is a full, clear, and exact description thereof.

This invention relates particularly to portable joints of the type disclosed in a patent granted to me on July 8, 1913, under 1,066,751, and comprises a carrier and a clamping member, the carrier consisting of prolate guides extending continuously from end to end thereof and formed to accommodate the clamping member and receive portions of the rope or wire crimped thereby. For full comprehension, however, of my invention reference must be had to the accompanying drawings forming a part of this specification in which similar reference characters indicate the same parts, and wherein:

Figure 1 is a plan view of my improved joint with two portions of a wire rope to be united lying therein ready to be clamped, the carrier member being shown partly in longitudinal sectional view; Fig. 2 is a transverse sectional view taken on line A A Fig. 1; Fig. 3 is a side elevation of the device; Fig. 4 is a plan view of my improved joint in the act of being closed upon two portions of a wire rope to unite such portions to form a loop; Fig. 5 is a detail side elevation of the clamping member removed; Fig. 6 is a plan view thereof; Figs. 7 and 8 similar views respectively of a modification; and Fig. 9 is a plan view of a plate cut ready to be forged to present my improved carrier.

The carrier member consists of a plate-like device *b* with its side edges bent back upon itself in curved form to present a pair of guides *c* extending in length from end to end of the carrier, such guides being formed with lateral openings or slots *d*.

The clamping member consists of a bar the opposite ends of which are formed with cam faces *e* sheared off at their forward sides, *f*, relatively to movement in counter-clockwise direction. A square boss *g* is cast in one with or otherwise formed as an integral part of the bar and such boss and bar and carrier member are correspondingly centrally bored to receive a pintle prefer-

ably in the form of a rivet *h*. This clamping member may be formed either as shown in Figs. 5 and 6 with the cam ends finished with flat faces or as shown in Figs. 7 and 8 with such faces grooved to conform to the rope or wire to be engaged thereby.

In order to secure a proper gripping of the ends of the rope or wire the slot at one side of the carrier is located a short distance nearer one end thereof and a slot at the other side a short distance nearer the opposite end of the carrier, such slot being of a length to permit the cam ends of the clamping member to displace the rope or wire thereunto and as such clamping member approaches a position at right angles to the carrier to crimp the rope or wire upon the end wall *k* of the slot.

I prefer to forge my carrier member from a plate the dimensions of which may be varied to suit different sizes of joints. I find a square plate most suitable for making carrier members for joints uniting sections of five-sixteenths wire cable. In order to obtain the best results the slots of the carrier member and the cam face of the clamping member must be made and relatively disposed proportionately with relation to the thickness or gage of the cable rope or wire to be united and in order that the proper proportions may be understood I will now describe the development of a joint for one-half inch wire cable or rope for purpose of illustration.

The diameter of gage of the cable rope or wire to be united is used as the basis of calculation. A half inch pintle will allow a margin of safety in strength of metal against shearing and strain due to any weight the cable may be called upon to withstand. In Fig. 9 the circle *m* is described equal in diameter to the pintle. Space is provided at each side of this circle for the width of the clamping member and to permit the cable to pass, such spaces being of a width equal to about three and one-half times the diameter of the pintle hole from each side of such hole. A circle 1 concentric with the pintle hole and equal in diameter to three times that of the hole is described and a second concentric circle 2 three and one-half times the diameter of the pintle hole is then described, and a third concentric circle 3 four times the diameter of the pintle hole. Parallel lines 4 and 5 are then drawn at right angles and transversely to

the plate and touching the circle 1. Space is then allotted for the concave wings forming the guides from the plate surfaces at the outer sides of the lines 4 and 5 and equal 5 in extent to approximately three times the diameter of the pintle hole, allowance being made for shrinkage in forging. At the point of intersection of the parallel lines 4 and 5 with the circle 2, at the right above 10 the pintle hole and at the left beneath it, lines 6 and 7 are drawn across the plate surfaces 10 and at right angles to such lines 4 and 5. These lines 6 and 7 establish the 15 positions of the slot ends k upon which the rope cable or wire ends are crimped. (It may be mentioned here that this location is for a right hand lock). The lines forming the inner walls k' , relatively to the carrier, of the slots d are then drawn as at 12 parallel to the lines 4 and 5 touching the circle 3 and extending from the lines 6 and 7 to 20 lines 13 drawn at right angles to the lines 4 and 5 from end to end of the plate and touching the circle 1. The lines 14 representing the outer walls k^2 of the slots d are 25 then drawn parallel to the lines 12 and spaced therefrom a distance slightly greater than the diameter or gage of the wire cable, rope, or wire to be united. These measurements 30 determine the proper proportions in length of slots and relative positions thereof proportionately to the wire cable, rope, or wire, and the cam faced clamping member is laid out proportionately relatively to the 35 wire cable, rope or wire as follows:—

Referring to Fig. 6: On the center 16 are described the circle 17 for the pintle and a second circle 18 equal in diameter to the circle 1 (Fig. 9) and on centers 21 and 22 at 40 a distance on each side of the center 16 about three-eighths greater than the diameter of the pintle hole 17 are described a pair of circles 19 and 20 equal in diameter to circle 18. The width of the clamping member is 45 then established by measuring off at each side of the pintle hole 17 and on a line 23 intersecting the centers 21, 16 and 22 a distance equal to the diameter of the pintle hole. Lines 24 and 25 are then drawn at 50 right angles to the lines 23 and intersecting the circles 18, 19 and 20. The outline of the clamping member is defined by a line extending from point of intersection of line 24 with circles 20 at the right of the line 23 and below the center 16 horizontally to the point of intersection with the circle 18 then following the circle 18 to the point of intersection with circle 19 then following circle 19 to the point where this circle is 55 intersected by the line 25 then along the line 25 to the point of its intersection with circle 18 following this circle to the point of intersection of circle 20 which is followed to 60

line 24. In this manner the length and breadth of the cam surfaced clamping member is established. This member may be rotated on its pintle in the circle 18. 65

Operation: By turning the clamping member clock-wise the cam-faced ends are caused to bear upon the portions of the 70 cable rope or wire lying in juxtaposition with slots thus forcing such portions outwardly and crimping them upon the end wall k of such slots. The effect is that when the member is turned firmly to this position 75 it will be locked there by the tension upon the cable rope or wire and remain locked until the member is forced back again into longitudinal position relatively to the carrier, the particular proportional dimensions 80 being important in securing proper locking and the prevention of the cable rope or wire from slipping or the lock from loosing its grip. The eccentric nature of the faces of the clamping ends adapt them for bending 85 and crimping into the slots the cable rope or wire however strong and stiff.

In constructing the carrier it must be carefully observed that the pintle hole is located midway between the parallel lines 13 90 extended from the opposite ends of the respective slots. This will, with proper length of slots, place the pintle in proper position relatively to the ends k of the slots upon which the portions of the cable rope or wire 95 are crimped.

The particular manner of laying out the joint may be varied without departing from the spirit of my invention.

What I claim is as follows:—

A portable joint for the purpose set forth comprising an abutment member having continuous guides extending throughout the main length of the same, said guides having the ends of the openings offset relatively 105 to each other each of said openings having a portion intersecting a plane extending transversely to the abutment member and in which the pivot of the clamping member is located, a clamping member, capable of 110 making a complete revolution, pivotally connected to the abutment member and having a pair of oppositely projecting jaws, the distance between one end wall of each opening and the arc described by the end of 115 each jaw being less than the diameter of the cable rope or wire to be joined for the purpose of crimping the same upon the said end walls.

In testimony whereof I have signed my 120 name to this specification in the presence of two witnesses.

JOHN PARK.
